UNITED STATES PATENT OFFICE.

LEROY F. HINTZ, OF CHICAGO, ILLINOIS, ASSIGNOR TO ALEC J. GERRARD, OF MENLO PARK, CALIFORNIA.

METHOD OF AND APPARATUS FOR BRACING AND SECURING MERCHANDISE PACKAGES FOR TRANSIT.

Application filed April 10, 1926. Serial No. 101,076.

This invention relates to a method and apparatus for bracing and securing merchandise packages for transit.

The object of the invention is to provide a method of and apparatus for bracing and securing merchandise packages, which is simple, economical, easily applied and efficient in use.

A further object of the invention is to provide a method and apparatus of the nature referred to, to efficiently brace and secure merchandise packages or articles against relative movement with respect to each other in a group or mass assembly.

A further object of the invention is to provide a method of and apparatus of the nature referred to wherein weaving movements of individual packages or articles of merchandise assembled into a group or mass assembly is prevented or minimized.

Other objects of the invention will appear more fully hereinafter.

The invention consists substantially in the mode of procedure, apparatus and arrangement of parts, all as will be more fully hereinafter set forth and illustrated in the accompanying drawing and finally pointed out in the appended claims.

Referring to the drawings and to the various views and reference characters appearing thereon, Fig. 1 is a view in top plan somewhat diagrammatic, showing a portion of a carrier with a plurality of merchandise units or articles assembled, braced and secured together into a unitary group or mass assembly in accordance with the principles of my invention.

Fig. 2 is a broken view in section on the line 2—2, Fig. 1 looking in the direction of the arrows.

Figs. 3, 4 and 5 are detail views, respectively, in front, side and end elevation of a form of spacer rod suitable for use in carrying out my invention.

Fig. 6 is a view in perspective of a group or unit assembly of individual articles of merchandise braced and secured in accordance with the principles of my invention.

The same part is designated by the same reference numerals wherever they occur throughout the several views.

The transportation of merchandise by the usual transporting carriers, such as freight cars, trucks, boats, ships or the like has

become a matter of very great importance by reason of the injury and damage to such transported merchandise, which has resulted from methods heretofore employed, and for which damage, injury and wastage no adequate remedy has been offered prior to my invention, as set forth in my pending applications, Ser. No. 56,741, filed September 16, 1925 and Ser. No. 68,421, filed November 11, 1925.

The problems encountered in effecting safe transportation of merchandise are very serious ones, because of the rough usage which motor trucks, freight cars, and other carriers are subjected to and the conditions of roadways or trackage and the usual methods of switching and making up freight trains and the handling of such trains. Merchandise transported by such carriers are, of course, subjected to the shocks, jars and jolts resulting from such methods of handling and operating the carriers. The loss from injury and damage encountered in freight or merchandise transportation amounts annually to enormous figures.

In my applications above referred to, I have provided a system of merchandise stowage wherein individual packages are disposed in groups or bound together into a unitary mass or group assembly against movement of the individual packages, composing the group or assembly, whereby the assembly or group of packages is unattached and free from movement, restrained only by the inertia of its own group weight. I have found such a method of stowage and securing of the packages to be highly efficient and to avoid the very great loss, damage and injury that has heretofore been experienced, as well as the expense incurred in former attempts to prevent such injury and loss through the use of lagging.

I have found, however, that in the case of merchandise packages of various sorts when assembled and bound together, according to the inventions of my former applications, above referred to, there is a tendency of the assembly or bound individual members of the group assemblies to sway, rock or tilt more or less while in transit, by reason of the swaying, rocking, tilting or weaving movements of the carrier. This is particularly true in the case of motor trucks, and freight cars due as I believe to pendulum ac-

tion resulting from the operation of the truck or car under various conditions of speed and for various characters of roadways or roadbeds. Likewise, I find the 5 same tendency in ship or boat transportation, due to the rocking of the boat in rough waters.

It is among the special purposes of my present invention to provide a method and 10 apparatus, which is simple, easily applied and effective for overcoming and preventing the effects of any tendency to weave, rock or tilt the individual units composing the assembled or bound group of merchandise 15 packages.

In accomplishing these special objects and purposes of my present invention, I employ, in one form of my invention, binders which are applied adjacent the upper and lower 20 ends of assembled vertically disposed merchandise packages, said binders being spaced and held apart from each other and applied around the assembled group or mass of packages under tension and maintained under 25 such tension. I then interconnect the spaced apart binders by bracing them diagonally, the one to the other. In a further embodiment of my invention, I arrange the diagonal interbracing so as to alternately brace the 30 upper and lower portions of the assembled packages.

Referring specifically to the illustrations of the applications of my invention, as shown in the drawings, 10 designates a carrier which may be a motor truck body, freight car or other form of merchandise carrier, 11, see Figs. 1 and 2 indicates a plurality of merchandise packages disposed in upright or vertical position and assembled 35 into a group or unit assembly, to the upper and lower end portions of which are applied the binders 12, 13, respectively, said binders being applied around the assembled group of packages and maintained 40 tightly applied therearound under tension, said binders 12, 13 being spaced apart, from each other by suitable spreader rods or members 14. These spreader members in the particular form shown have their ends 45 formed into loops 15 to receive the binders 12, 13 respectively. Interconnecting the spaced apart binders 12, 13 are diagonally disposed brace members 16, 17.

In practice the upper ends of the diagonal 55 brace members 16, 17 are secured in any suitable manner in loops 18, see Fig. 2 at the upper ends of certain of the spacer rods 14 and their lower ends in loops 19, at the lower ends of other of said spacer members.

60 Under normal circumstances, the greatest tendency of the units, composing the assembled and bound together group to tilt or rock occurs in those members of the assembled group of packages occupying the front and rear and outer portions of the

group. That is to say, the effects of any swaying or tilting tendency that develops in all the packages composing the group or mass assembly, exercise a cumulative effect upon the upper binder 12 where said binder comes 70 in contact with the outer-members of the assembled group. I have found, however, that by interbracing the spaced apart binders by the diagonal brace members any undue strain imposed upon the upper binder by 75 the tilting or rocking tendency referred to is effectively distributed through the diagonal bracing members to the lower binder and said strain is resisted resulting in very 80 efficiently holding and maintaining the packages in proper relation in their group assembly.

In the case of certain kinds of articles of merchandise to be transported, I have found it desirable to continue the interbracing throughout the entire circumference of the assembled packages by disposing the diagonal bracing members to extend continuously from a point at the lower portion of the assembly to a point adjacent the 85 upper portion thereof, and thence down again to the lower portion thereof in continuous direction around the assembled articles. Such an arrangement is shown at Fig. 6, wherein the diagonal brace member 90 20, for example, commencing at an upper end part or corner of the assembled merchandise articles, as indicated at 21, extends diagonally downwardly to a point indicated at 22, thence upwardly diagonally 100 to the point 23 and so on all the way around the assembled articles. An alternately disposed diagonally arranged brace member 24 105 is also shown and applied in accordance with my invention. These diagonal brace members may if desired be interconnected with other binders 25, 26, which are also applied around the assembled merchandise units or articles, and I have shown said brace members 20, 24, so interconnected as at 27, with 110 the transversely applied binders 25.

In this arrangement, instead of employing spacing members of the nature indicated at 14, in Figs. 1, 2, 3 and 4, merely wooden bars are used with staples forming the eyelets to effect the desired interconnection of the binders. Where the merchandise articles are of more or less rectangular shape thereby forming corners in the assembled mass, the wooden bars 28 may be applied 115 on opposite sides of the corners as means for securing by stapling or otherwise, the diagonal brace members, which pass around the corners. These likewise form brackets for protecting the merchandise articles at 120 the corner. By employing bars 28, which may, of course, be any other suitable material besides wood, I avoid the necessity of using any special form of spacer rod and such bars afford means for protecting the 125 front and rear and outer portions of the 130

merchandise articles against injury through the cutting or pressing action of the binders, when tension is applied thereto.

While, I have shown a particular form of spacer member in Figures 3, 4 and 5, for use in connection with my present invention, I do not claim the same herein as this form of spacer member is covered and claimed in my application filed of even date herewith. It will be obvious to a person skilled in the art that various changes in the details of structure and arrangement and in the method of applying and disposing the diagonal bracing members may be made without departure from the spirit and scope of my invention. It is also obvious that my invention is not to be limited or restricted to the use of single binders, as the same may be duplicated, as is obvious.

20 It is to be understood that the binders 12, 13 and likewise interbracing members 16, 17, 20, 24, 25 and 26 are to be applied to and around the assembled group of merchandise packages or articles under tension.

25 The tension of these binders may be accomplished in various ways, as for instance in the manner described in my pending applications Ser. No. 56,741 and No. 68,421, above referred to. Any desired type, structure 30 or character of binder may be employed in carrying out my invention and the same is true with regard to the interbracing members. After the binders and interbracing members are sufficiently tensioned around

35 the assembled group of articles or packages their ends are secured together in any suitable or convenient way. Where binder wires are employed for the binders and interbracing members, said binders and interbracing members are secured in applied position and under tension by intertwisting them together to form knots 30, thereby retaining the tension upon said binders and interbracing members while in their applied 40 positions.

Having now set forth the objects and nature of my invention and structural arrangements and a mode of operation embodying the principles thereof, what I claim 50 as new and useful and of my own invention and desire to secure by United States Letters Patent is:

1. The method of bracing and securing merchandise packages for transit which consists in assembling the individual packages or articles of merchandise into a group assembly and applying under tension therearound binders at relatively different portion of the lengths of said articles or packages, and then interconnecting said binders with diagonally disposed braces under tension.

2. The method of bracing and securing merchandise packages for transit, which 65 consists in assembling the articles or pack-

ages, into a group or mass assembly, then applying binders tightly around the assembled group adjacent opposite ends of said articles or packages and interconnecting said binders with diagonally disposed bracing members.

3. The method of bracing and securing merchandise packages for transit, which consists in assembling the articles or packages into a group or mass assembly, then applying a binder tightly around the assembled group adjacent opposite ends of said articles or packages and interconnecting said binders with diagonally disposed bracing members extending continuously around the assembled group and alternately from the one binder to the other.

4. In an apparatus for bracing and securing merchandise packages for transit the combination with binder means applied around an assembled mass of individual units or packages of merchandise in spaced apart relation to each other of diagonally disposed bracing members connecting said spaced apart binder means.

5. In an apparatus for bracing and securing merchandise packages for transit, binders disposed in substantially parallel relation and arranged to surround and bind together the mass of packages at points adjacent the respective ends thereof, in combination with bracing members interconnecting said binders and disposed in diagonal relation with respect thereto.

6. In an apparatus for bracing and securing merchandise packages for transit, binders disposed in substantially parallel relation and arranged to surround and bind together the mass of packages at points adjacent the respective ends thereof, in combination with bracing members interconnecting said binders and disposed in diagonal relation with respect thereto, said binders and interconnecting members being applied and maintained under tension.

7. In an apparatus for bracing and securing merchandise packages for transit, binders arranged to surround a group of individual merchandise articles or units, means to space said binders apart from each other in their applied position and diagonally disposed bracing members interconnecting said spaced apart binders.

8. In an apparatus for bracing and securing merchandise packages for transit, binders arranged to surround a group of individual merchandise articles or units, means to space said binders apart from each other in their applied position and diagonally disposed bracing members interconnecting said spaced apart binders, said bracing members and binders being maintained under tension in their applied relation.

9. In an apparatus for bracing and securing merchandise packages for transit

binders arranged to surround a group of individual merchandise articles or units, means to space said binders apart from each other in their applied position and diagonally disposed bracing members interconnecting said spaced apart binders, said diagonally disposed bracing members continuing

around the group of assembled articles or packages and alternately connecting said binders.

In testimony whereof I have hereunto set my hand on this 1st day of April A. D., 1926.

LEROY F. HINTZ.
